UNITED STATES PATENT OFFICE.

ALBERT H. KEMPER, OF DAYTON, OHIO.

PICTURE-HOOK.

No. 888,819.

Specification of Letters Patent.

Patented May 26, 1908.

Application filed February 8, 1908. Serial No. 414,868.

To all whom it may concern:

Be it known that I, ALBERT H. KEMPER, citizen of the United States, residing at Dayton, in the county of Montgomery and State 5 of Ohio, have invented certain new and useful Improvements in Picture-Hooks; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 This invention relates to improvements in picture hooks of the kind which are attachable to molding for the suspension of pictures.

The object of the invention is to provide such picture hook with means for enabling it 20 to be placed upon the molding or removed therefrom without necessitating the standing upon a chair or ladder.

The invention relates specifically to means 25 on the picture hook enabling the use of a rod or suitable stick by means of which the picture hook is engaged and is removed from or placed upon the molding with one hand while the other hand of the person may hold the picture while the hook is being so placed upon 30 or removed from the molding.

Preceding a detailed description of the invention, reference is made to the accompanying drawings, of which—

Figure 1, is a top view of a picture hook 35 having my improvement applied thereto: Fig. 2, is a side view showing the picture hook engaging molding. Fig. 3, is a front view of the picture hook. Figs. 4-5 and 6, are similar views of the picture hook with 40 modified means thereon for removing and replacing said hook. Fig. 7, is a view of the end of a rod or stick having means thereon adapted to coöperate with the means on the picture hook for removing and replacing said hook.

In a detail description of the invention, similar reference characters indicate corresponding parts.

For the purposes of my invention, the ordinary metallic picture hook 1 is utilized, 50 said hook being supported upon molding 3 in the usual manner. From the upper part of said picture hook there is stamped a tongue 2 assuming a position at right angles to the hook and in the front thereof. This 55 tongue 2 is provided with an aperture 4 which is designed to receive a pin 5 secured to the end of a rod or stick 6. The pin 5 may be an ordinary pin and the rod or stick 6 may conveniently be a broom handle. 60 The pin 5 is insertible in the aperture 4 in said tongue 2 and by means of said rod or stick the picture hook is elevated to be placed upon the molding or may be moved from the molding; the person performing the operation 65 in either case is thus relieved of the necessity of standing upon a chair or ladder.

The modification shown in the drawings, Fig. 4, consists of a bolt 7 rigidly secured to the front of the picture hook and extending 70 outwardly at right angles thereto in the manner of the tongue 2. This bolt is provided with an eye 8 which is adapted to receive the pin 5 and to thus enable the picture hook to be supported upon the end of the rod 75 or stick in a manner similar to the tongue 2.

I claim:

1. A picture hook having a member projecting from the outer side thereof and provided with an aperture adapted to receive a 80 pointed instrument and by means of which the picture hook may be elevated to or removed from a molding, substantially as specified.

2. A picture hook having an eye bolt secured to its outer side by means of which said picture hook may be elevated to or lowered from a molding, substantially as 85 specified.

In testimony whereof I affix my signature, 90 in presence of two witnesses.

ALBERT H. KEMPER.
